E. L. GAYLORD, OF TERRYVILLE, CONNECTICUT.

Letters Patent No. 60,874, dated January 1, 1867.

IMPROVEMENT IN DRAWER LOCKS.

The Schedule referred to in these Letters Patent and making part of the same.

TO ALL WHOM IT MAY CONCERN:

Be it known that I, E. L. GAYLORD, of Terryville, in the county of Litchfield, and State of Connecticut, have invented a new and improved Lock; and I do hereby declare that the following is a full, clear, and exact description thereof, which will enable others skilled in the art to make and use the same, reference being had to the accompanying drawings, forming part of this specification, in which—

Figure 1 is an internal view of my invention, the case being in section, as indicated by the line $x\ x$, fig. 2.

Figure 2, a transverse section of the same, taken in the line $x'\ x'$, fig. 1.

Figure 3, a section of the same, taken in the line $y\ y$, fig. 2.

Figure 4, a transverse section of the same, taken in the line $z\ z$, fig. 3.

Figure 5, a horizontal section of the same, taken in the line $z'\ z'$, fig. 3.

Figure 6, a detached view of the key of the lock.

Similar letters of reference indicate like parts.

This invention more especially applies to drawer locks, and small locks generally, which are placed upon parts adjacent to each other, such, for instance, as the drawers of a bureau, the small doors of a secretary, etc., and which should be provided with different keys, so that one key cannot unlock more than one lock. Hitherto these locks have been expensive to manufacture on account of each lock requiring a different adjustment of tumblers; and the object of this invention is to overcome that difficulty, by having the tumblers the same in each lock and introducing adjustable wards, by which means each lock can be provided with a key different from the others at a comparatively trifling expense.

A represents the lock case, and B the bolt fitted therein. C is a tumbler, which is fitted on a pin or stump, a , the latter passing through an oblong slot in the bolt B, and also through a series of wards, D, on or over which the bolt slides, the tumbler C being fitted on or over the bolt, and the latter having a pin, b , projecting from it and into a slot in the tumbler, the pin and slot requiring the tumbler to be moved a certain distance by the key before the bolt can be moved. This arrangement, however, is well known and very old, and I design to have the tumblers of all the locks, or a given series of locks, made precisely the same, so that there will be no difficulty in applying the tumblers. In order, however, to have a different key for each lock, or to prevent one key from unlocking more than one lock, the one for which it was made, I employ a series of wards, D, placed one over the other. These wards are simply metal plates having lips, c , projecting from them within the path of the rotation of the bit of the key. These lips are of different lengths, and the bit d of the key has slots, e , cut in it of different depths, to correspond to the length of the lips c of the wards, so that the bit may pass the same; and it is designed to have the lips c of the wards in the several locks all differ as regards length, so that no key will fit two locks. It is a very simple matter to make and adjust the wards D to suit the keys, as they are all fitted loosely on the pin a , so that they may turn thereon, and a screw, f , passes through an oblong slot, g , in the wards, and into the rear plate of the lock case, (see fig. 3,) and by relaxing this screw the lips c may all be adjusted accurately to the slots e in the bit of the key.

I claim as new, and desire to secure by Letters Patent—

The adjustable wards D, in combination with the bolt B and one or more tumblers C, arranged substantially in the manner as and for the purpose herein set forth.

E. L. GAYLORD.
